UNITED STATES PATENT OFFICE.

FRED. W. SNOW, OF HILLBURN, NEW YORK.

SWITCH-STAND.

SPECIFICATION forming part of Letters Patent No. 320,507, dated June 23, 1885.

Application filed February 11, 1885. (No model.)

To all whom it may concern:

Be it known that I, FRED. W. SNOW, a citizen of the United States, residing at Hillburn, county of Rockland, and State of New York, 5 have invented certain new and useful Improvements in Switch-Stands, of which the following is a specification.

My invention relates to switch-stands, and has for its object to improve the construction 10 and operation of such stands; and to this end my invention consists in the peculiar construction and arrangement set forth hereinafter.

In the drawings forming part of this specification, Figure 1 is a side elevation of a stand 15 embodying my invention, showing the handle raised ready to be turned. Fig. 2 is a similar view, partly in section, showing the position of the parts when the switch is being operated by the train, and Fig. 3 is a transverse section on the line 1 2.

The frame or body A of the stand supports a block, a, which is secured to or slides in the frame of the stand, and is recessed for the passage of a target-shaft, B, which passes through 25 a heavy weight or head-block, D, having at the lower side teeth c, with beveled sides, intermeshing with corresponding teeth, e, upon the block a.

At the upper side of the head-block D is a 30 rectangular recess, x, shown as square in the drawings, adapted to a square projection, d, at the underside of a block, E, which slides freely upon the target-shaft, but is prevented from turning thereon either by means of a feather 35 or by making the shaft angular in cross-section, as shown.

As a means of raising and lowering the block E, I pivot the hand-lever F to a sleeve, H, secured to the target-shaft, and connect said lever by links G to opposite sides of the block E, which will therefore rise when the lever is lifted and descend when the lever is depressed. 40

The target-shaft is provided at the lower end with the usual crank, C, adapted for connection with the rod extending to the switch, and a spring, f, coiled around the target-shaft, bears at the upper end against the block a and at the lower end against the collar i upon the shaft, and tends to raise the former. 45

50 When the switch-rails are to be set to a dif-

ferent position from any which they may occupy, the hand-lever F is raised until the projection d of the block E is removed from the recess x, when the target-shaft may be turned by means of the lever so as to set the switch-rails in the desired new position, in which they will be secured by depressing the hand-lever until the block E is in contact with the head-block D. So long as the parts occupy the position last described the switch-rails will be 55 held in place, because the head-block is prevented, by the interlocking of the teeth c e, from rotating, and the shaft B cannot be turned without also turning the block E, which can have no rotation independent of the head-block D while the projection d is in the recess x. While the switch-rails are thus prevented from moving under any ordinary circumstances, they are protected against destructive action by the capacity of the block a to be 60 depressed when sufficient force is applied to the crank to cause the teeth c to slide upon and ride over the teeth e. Thus when excessive pressure is brought upon the switch-rails the thrust upon the crank C will tend to turn the 65 shaft B, and with it the head-block D, and to cause the faces of the teeth c to bear upon those of the teeth e, so that the upper teeth will slide upon and over the lower teeth, forcing the block a downward against the spring, 70 thereby permitting the rails to move without breaking. At the same time the tendency of the spring f to hold the block a in its highest position is so great that this yielding action 75 cannot result except under extraordinary circumstances. 80

While I have described the projection d and recess x as being rectangular, the sectional forms thereof will depend upon the number of positions to which the switch-rails are to be 85 set. Thus when the said rails are to be set in four positions the projection and recess are rectangular, but if the rails are to be set only in three different positions the projection and recess would be triangular. 90

In order to prevent unauthorized tampering with the switch, I provide means for locking the hand-lever to the head-block, whatever may be the position of the lever in respect to the 95 said block. Thus I provide the block with a 100

number of pairs of radiating ears, s , corresponding to the number of sides to the projection d , each pair of ears having a perforation, y , for the passage of the keeper of a padlock, so that 5 the lever cannot be raised from contact with the ears while the lock is in position.

I claim—

1. The combination, in a switch-stand, of a frame, A , provided with a sliding block, a , or 10 portion having beveled teeth e , a target-shaft having a crank at the lower end, extending through the block and carrying a sliding head, E , with an angular projection, d , at the lower side, and means for adjusting the said head 15 vertically, a head-block, D , arranged above the block a , provided with corresponding teeth, and having at the upper side a recess corresponding to the projection d , all substantially as set forth.
2. The combination, with the stand, crank-shaft, a sliding and non-rotating toothed block, 20

a , sliding and rotating block E , and intervening head-block D , having a recess adapted to a projection, d , of radiating ears s upon the head-block, corresponding in number to the 25 number of sides of the projection d , substantially as set forth.

3. The combination of the stand A , toothed block a , crank target-shaft B , block E , having a projection d , block-operating lever F , connected to the block E , head-block D , having teeth at the under side and provided with a recess adapted to receive the projection d , and with ears s , all substantially as set forth.

In testimony whereof I have signed my name 35 to this specification in the presence of two subscribing witnesses.

FRED. W. SNOW.
